UNITED STATES PATENT OFFICE.

WILLIAM GRIKSCHET, OF DETROIT, MICHIGAN.

PRIMING DEVICE FOR INTERNAL-COMBUSTION ENGINES.

1,248,649.

Specification of Letters Patent. Patented Dec. 4, 1917.

Application filed December 17, 1915. Serial No. 67,311.

To all whom it may concern:

Be it known that I, WILLIAM GRIKSCHET, a citizen of the United States, and resident of Detroit, in the county of Wayne and

5 State of Michigan, formerly of the city and county of New York and State of New York, have invented certain new and useful Improvements in Priming Devices for Internal-Combustion Engines, of which the following is a specification.

10 This invention relates to a type of valve, structure designed for use as a priming device for internal combustion engines.

The object of my invention is to provide 15 a priming device of simple and efficient construction whereby when the valve element thereof is open a direct uninterrupted inlet or outlet is afforded between the interior of the engine cylinder and the atmosphere, and 20 whereby also such inlet or outlet, as the case may be, can be readily closed and effectually sealed, as requirements may demand.

A further object of my invention is to 25 provide a priming device of such construction that when the inlet or outlet is sealed dust accumulation in the priming cup and valve seat is avoided, thus obviating the otherwise liability of such dust being 30 washed into the cylinder during the priming operation and causing wear and tear on the pistons, cylinders and valves, and also liability of such dust entering the valve seat and causing undue wear thereon.

35 My invention comprises an apertured element for connection with an engine cylinder, a socket member adjustably mounted on said element, and a valve element permanently mounted in said socket member and 40 including a rotary member having a tubular extension which projects beyond the socket member and affords a supply or discharge portion which can be set to open or closed position with respect to the apertured element, as will be hereinafter described and claimed.

In the drawings—

Figure 1 is an elevation of a priming device embodying my invention, showing the 50 same as applied to a section of an engine cylinder. In this view the feed cup and its integral valve member are shown as positioned for the feeding of a priming charge to the cylinder; the dotted lines indicating 55 such cup and valve member in closed position.

Fig. 2 is a longitudinal vertical section of the device in open position.

Fig. 3 is a similar section on a plane at right angles to Fig. 2.

Fig. 4 is a section similar to Fig. 2, but showing the valve as set and locked in sealing position.

Fig. 5 is a horizontal section, as on the line 5—5 of Fig. 4.

Fig. 6 is a section similar to Fig. 2, illustrating a modification of the invention.

Fig. 7 is a section on a plane at right angles to Fig. 6.

Referring to the drawings, 10 designates 70 a part of an engine cylinder to which a priming device embodying the principle of my invention is applied. This device in its preferred form comprises a centrally bored plug 11 externally screw-threaded at its 75 upper and lower ends, as at 12 and 13 respectively. The lower end 13 of the plug is screwed into the internally-threaded apertured portion of the engine cylinder. On the upper portion of the plug is screwed 80 a cap or socket member 14 the upper portion of which is slotted to provide two spaced up-projecting lugs 15 which are bored to receive a cylindrical cross-piece 16. This piece is forcibly driven into the per- 85 forations of the lugs 15 so as to be fixedly held thereby. The body of the cross-piece is provided with a diametrical port 17 in axial alinement with the bore of the plug; such cross-piece constituting, in effect, a 90 fixed valve member.

Snugly fitted between the lugs 15 and rotatably mounted on the body of the pin, is a flat circular head 18 having a diametrical port 19 which, by actuation of the head, can 95 be moved into or out of axial alinement with the port 17 of the cross-piece. The head thus constitutes a relative movable valve member which is a permanent part of the socket member. The head is formed on 100 the lower end of an expanded cup-like extension 20 which is in direct axial communication with the valve port 19. When the cup occupies the upright position shown in Figs. 1, 2 and 3, the ports of the respective valve members are in registry, and a direct open 105 passage is thus afforded between the cup and the interior of the engine cylinder to permit the ready introduction of a priming charge of gasoline or other volatile hydrocarbon to 110 the cylinder. In case the passage should become clogged by the lodgment therein of car-

bon or other obstruction, a cleaning wire or the like can be readily run through the direct passage and the obstruction thus be removed with facility.

- 5 By grasping the cup and swinging it from the vertical, either to the right or left, as indicated by the dotted lines in Fig. 1, the ported valve member 18 can be readily positioned to interrupt the communication of its
10 port with that of the fixed member 16 and thus seal the mouth of the plug passage, and then by properly turning the cup about the axis of the plug the socket member can be screwed down and the circumferential edge
15 of the member 18 forced hard down upon and clamped against the opposing seat portion of the plug. Thus the plug passage is effectually closed and the valve is securely locked in sealing position. (See Figs.
20 4 and 5.)

The device above described is simple in construction and effective in operation. It well fulfils the objects of my invention above mentioned. Its constituent parts can
25 be cheaply made and readily assembled, and as the cup and valve head are permanently attached to the socket member, the latter, in virtue of its screw connection with the plug, can be readily adjusted to compensate for any wear at the valve seat.

In Figs. 6 and 7, I have shown a slight modification of my invention wherein the ported cross-member is omitted and instead thereof the ported circular head 18 is not only shaped to occupy the space between the

upstanding walls or lugs of the adjustable socket member 16, but such head is provided with centrally-disposed lateral sockets 21 into which the said walls or lugs are stamped or otherwise pressed to afford permanent
40 pivot bearings 22 for the circular head.

What I claim is—

1. A device of the character described comprising a vertically apertured plug, a socket member screwed thereon having an
45 upwardly projecting portion, a ported valve member fixedly held in said projecting portion, and a complementary ported member rotatably mounted on said fixed member, and having a projecting feed member in
50 axial alinement with the port of said complementary member.

2. A device of the character described comprising a vertically apertured plug, a socket member screwed thereon having a
55 pair of spaced upwardly projecting lugs, a valve member fixed in and between said lugs having a diametrical port in axial alinement with the bore of the plug, a circular valve member rotatably mounted on said fixed member having a diametrical port movable into and out of registry with the port of the
60 fixed member, and an integral feed member projecting from said rotatable valve member.

Signed at Detroit in the county of Wayne and State of Michigan, this 13th day of December, A. D. 1915.

WILLIAM GRIKSCHET.
